UNITED STATES PATENT OFFICE.

ARTHUR S. EVANS, OF ARVONIA, KANSAS.

AUTOMATIC AIR-BRAKE COUPLING.

No. 894,127.

Specification of Letters Patent.

Patented July 21, 1908.

Application filed March 11, 1908. Serial No. 420,417.

To all whom it may concern:

Be it known that I, ARTHUR S. EVANS, a citizen of the United States, residing at Arvonia, in the county of Osage and State of 5 Kansas, have invented new and useful Improvements in Automatic Air-Brake Couplings, of which the following is a specification.

This invention relates to improvements in automatic air brake couplers and couplers of 10 a like character designed for use upon railway cars for connecting the ends of fluid conductors upon the proximate ends of the cars of a train, the main object of the invention being to provide a simple and efficient 15 type of coupler which will be normally maintained in proper coupling position, which is adapted in operation to have universal motion to conform to the motion of the cars, which is provided with means for securing 20 an efficient cushioning action during the coupling operation, in which provision is made for holding the coupling head against independent motion when uncoupled, and in which the air feed valve therein will be automatically opened and closed when the coupling 25 is respectively engaged with and disengaged from the coupling of another car.

With the foregoing and other important objects in view, the invention consists of the 30 features of construction, combination and arrangement of parts hereinafter fully described and claimed, reference being had to the accompanying drawings, in which:

Figure 1 is a side elevation of the proximate ends of two coupled railway cars equipped with my invention. Fig. 2 is a bottom plan view of the connected air brake coupling shown in Fig. 1, the outlines of the car bodies being indicated in dotted lines. 40 Fig. 3 is a vertical longitudinal section through one of the automatic couplers. Fig. 4 is a perspective view of the coupling head thereof.

Referring to the drawings, the numerals 1 and 2 respectively designate the proximate 45 ends of two coupled cars equipped with my invention, and 3 and 4 designate, respectively, in a general manner the air brake coupling devices carried thereby, which, as shown in Figs. 1 and 2, are coupled to connect the train pipe sections 5 upon the cars with each other.

Each automatic coupling device comprises a coupling head 6 having a beveled abutting face 7 to engage the reversely beveled face of 55 a coacting coupling, it being understood that the heads at opposite ends of a car have their

upper and lower surfaces respectively beveled so that the beveled faces of opposing couplings upon the proximate ends of cars will mate and fit snugly together. Each 60 coupling head is also provided with lateral stop shoulders 8 for an obvious purpose and with a yoke or strap 9 overhanging its bevel face to receive and engage the outer face of the coupling engaged therewith, thus providing for the frictional engagement of coupler heads tight enough to prevent leakage of air and yet loose enough to permit the heads to separate upon the uncoupling and movement apart of the cars. Each coupler head 70 is formed with a longitudinal bore opening through the bevel face thereof and in which is fitted a rubber tube or lining 10, which projects slightly beyond the bevel face to form a sealing disk or portion 11 which on engaging 75 the corresponding disk of another coupler will form an air-tight connection therewith to obviate all liability of the leakage through the coupler heads of the air flowing from car to car through the train pipe.

The coupler head is connected by an externally threaded bushing tube 12 with the forward end of a tubular shank comprising two sections 13 and 14 detachably connected by an interposed threaded bushing tube 15, 85 between which and the section 13 is inserted suitable packing 16 to prevent leakage of air at the joint. The shank section 13 is formed with an inlet tube or nozzle 17 connected by a rubber tube or hose 18 with the train pipe 5, 90 and the lower or inner end of said nozzle is in communication with the feed bore or passage formed by the tubes 10 and 12, at the inner end of which bore or passage is an elastic valve seat 19 for the automatic check valve 95 19 which is normally closed to prevent the escape of air through such feed bore or passage. The rear end of the shank section 16 carries a partially spherical head or ball 20 which fits and turns within a socket 21 100 mounted upon the forward end of a tubular draw-bar 22, which is movably mounted upon the car in a manner hereinabove described. The socket 21 is preferably constructed of sections suitably united to retain 105 the head therein, and carries an oil cup or lubricating device 22^a to keep the surfaces of said parts thoroughly lubricated. The stem 23 of the check valve 19 extends rearwardly through the coupling 15 into the shank section 14 and terminates when the valve is closed adjacent the forward end of a cyl-

drical bore or passage 24 in the head 20, in rear of which bore or passage said head is formed with a flared socket or recess 25. A coil spring 26 is disposed about the stem 23 5 between an adjusting nut 27 thereon and the coupling member 15 and tends to force the check valve open.

The shank 22 is slidably mounted for movement longitudinally of the car in a yoke shaped guide frame 28 having a cross piece 29, the shank being movable in said cross piece and the front cross piece of said frame. The frame is connected at its forward end with a bracket 31 and at its rear end with a bracket 32 secured to and depending from the bottom of the car, which brackets are reinforced by suitable inclined braces 33. The rear portion of the shank is reduced to form a seat for a coiled cushioning spring 34 bearing 20 at one end against the cross piece 29 and at its other end against a washer or shoulder 35 on the shank. This spring normally holds the shank projected forwardly to the normal limit of movement of the coupler, which position it occupies when disengaged from another coupler, and in which position the valve 19 is closed against the passage of air between the coupler head and train pipe. When the coupler is engaged by another 25 coupler and forced back, the spring absorbs the shock of impact and maintains the coupler under tension, so that the heads of the two couplers will be held firmly in contact.

A valve controlling rod 36 extends through 30 the shank and normally occupies the position shown in Fig. 3, in which its forward end occupies the bore 24 in the head 20 and abuts against the rear end of the stem 23. The rear end of the rod is forked, as at 37, and carries a pin 38 which has a loose pivotal engagement with the upper end of a lever 39, which lever is fulcrumed at its lower end on a fixed pin 40 carried by an arm 41 attached to the bracket 32. The lever forms a shifting motion transferring connection between the rod and shank, and to this end has a loose pivotal connection between its pivotal points 38 and 40 with a pivot pin 42 carried by a yoke 43 having a threaded stem 44, which 45 passes through one end of an arm 45 adjustably secured thereto by retaining nuts 46, the other end of said arm having a threaded engagement with the rear end of the shank 22 and being secured thereon by a retaining nut 50 47. The lever 39 normally stands in the inclined position shown in Fig. 3, in which its upper end lies in advance of its lower end, and is adapted to swing rearwardly to the substantially vertical dotted line position 55 when the shank of the coupler slides rearwardly from the impact and pressure of another coupler in the coupling operation, in which action the movement of the shank will be transmitted to an accelerated degree to 60 the rod 36, by which the automatic opening

of the valve 19 will be permitted for the flow of fluid through the joint coupling heads and to and between the air brake systems of the coupled cars.

From the foregoing description, it will be 70 apparent that in the normal position of the parts the feed valve will be held closed by the rod 36 against the pressure of the spring 26, while the forward end of said rod 36 occupying the bore 24 will lock the head 20 from movement in the socket 21, thus maintaining the head 6 in position to be engaged by the coupler on another car. When the head 6 is forced back by the other coupler to the extent permitted by the spring 34, the shank 22 75 will transmit motion through the connections 43 and 45 to the lever 39, which in turn through the greater range of motion of its upper end will transmit through the connections 37 and 38 an increased degree of rearward 80 motion to the rod 36. As a result, the forward end of the rod will move out of the bore 24 into the flared recess or socket 25, thus permitting the coupler head to have universal 85 motion to accommodate itself to the movements of the cars, while at the same time upon the pressure of said rod on the stem 29 being relaxed the spring 26 will open the valve 19, thus opening communication between the feed passages of the two connected 90 couplers and the train pipes on the cars. When the cars are uncoupled and the heads 6 move out of engagement the spring 34 restores the coupler to normally forwardly projected position and thus projects the rod 36 95 into interlocking engagement with the head 20 and to force the valve closed against the resistance of its opening spring.

Having thus described the invention, what is claimed as new, is:—

1. In an automatic air brake coupler, the combination of a longitudinally movable shank, a coupler head having a pivotal connection therewith and provided with a feed passage, an automatically opening valve controlling said passage, a cushioning spring for permitting rearward movement of the shank and returning the same to normal position, a valve controlling member normally arranged to hold said valve closed and the head from pivotal movement, and means for rendering said member inoperative upon the rearward movement of the coupling.

2. In an automatic air brake coupler, a rearwardly yielding shank having means for returning it to normal position, a head pivotally connected therewith and provided with a feed passage, an automatically opening valve controlling said passage, a movable member for normally holding the valve closed and the head from pivotal movement, and means operated by the recession of the shank from normal to coupling position to render said member inoperative.

3. In an automatic air brake coupler, a

- longitudinally movable coupler, means for cushioning the rearward movement of said coupler and returning the same to normal position, said coupler having a feed passage, a device for normally holding the valve closed, and means operated by the rearward movement of the coupler for rendering said device inoperative.
4. In an automatic air brake coupler, a spring controlled longitudinally movable shank, a head pivotally connected therewith and provided with a feed passage, a locking device for holding the head from pivotal movement, an automatically opening feed valve controlling said passage, means whereby in the backward and forward movements of the shank the locking device will be retracted and projected and the valve permitted to open in such rearward movement.
5. In an automatic air brake coupler, the combination of a longitudinally movable shank, a head pivoted thereto and provided with a feed passage, a spring for cushioning the rearward movement of the shank and returning the same to normal position, an automatically opening valve controlling said passage, a rod for normally locking the head from pivotal movement and holding the valve closed, and means operated by the movements of the shank for retracting and projecting said rod.
6. In an automatic air brake coupling, the combination of a movable shank, a spring for cushioning the rearward movement of said shank and returning the same to normal position, a head pivotally mounted upon the shank and provided with a feed passage, an automatically opening valve controlling said passage, a rod carried by the shank for normally holding the head from pivotal movement and the valve from opening movement, and an operative connection between the shank and rod, whereby in the rearward movement of the rod the shank will be adjusted to an inoperative position.
7. In an automatic air brake coupling, the combination of a movable shank, a spring for cushioning the rearward movement of said shank and returning the same to normal position, a head pivotally mounted upon the shank for universal movement and provided with a feed passage, an automatically opening valve controlling said passage, a rod carried by the shank for normally holding the head from pivotal movement and the valve
- from opening movement, and a lever connected with the shank and rod and operated upon the rearward and forward movements of the shank to move the rod to inoperative position and to restore it to operative position.
8. In an automatic air brake coupling, a movable spring cushioned shank, a coupling head pivotally connected therewith and provided with a feed passage, an automatically opening valve controlling said passage, a movable member for normally locking the head from pivotal movement and holding the valve from opening, and a variable movement connection between the shank and member for adjusting said member to an inoperative position in the rearward movement of the shank and restoring it to operative position upon the forward movement of the shank.
9. In an automatic air brake coupling, a sliding tubular shank, a spring for maintaining the same in normal position and permitting rearward movement thereof, a head pivotally connected with the shank and provided with a feed passage, an automatically opening valve controlling said passage, a sliding rod movable in the shank to normally lock the head from pivotal movement and hold the valve from opening, and connecting means between the shank and rod for retracting said rod upon the rearward movement of the shank.
10. In an automatic air brake coupling, a tubular shank having a socket, a coupling head having a portion mounted for universal movement in the socket and provided with a feed passage, an automatically opening valve controlling said passage, a rod endwise movable in the shank to engage and hold the head from pivotal movement and the valve from opening movement, a spring for maintaining the shank in normal position and permitting rearward movement thereof, and a pivotally mounted lever pivotally connecting the rod and shank to communicate accelerated rearward movement to the rod upon a corresponding movement of the shank.

In testimony whereof I affix my signature in presence of two witnesses.
